Wesley G. Carr,
ATTORNEY

UNITED STATES PATENT OFFICE.

JOHN ERNEST JOLLEY, OF STRETFORD MANCHESTER, ENGLAND, ASSIGNOR TO WESTINGHOUSE ELECTRIC & MANUFACTURING COMPANY, A CORPORATION OF PENNSYLVANIA.

SYSTEM OF VENTILATION.

Application filed October 6, 1920. Serial No. 415,065.

To all whom it may concern:

Be it known that I, JOHN ERNEST JOLLEY, a subject of the King of Great Britain, and a resident of Stretford Manchester, 5 in the county of Lancaster, England, have invented a new and useful Improvement in Systems of Ventilation, of which the following is a specification.

My invention relates to systems of ventilation and it has particular relation to apparatus for the ventilation of electrical and other machines or apparatus in which a circulation of air into, and out of, the machine is provided for the purpose of cooling and 15 ventilating the same.

In apparatus of the above indicated character, it has been heretofore customary, to provide air passages or ducts exterior to the machine which communicate with inlets and 20 outlets to and from the machine and which also communicate with the external atmosphere. Doors or shutters have been provided in the passages by the manipulation of which air may be caused to either circulate 25 in a closed circuit through the machine, and cooled by passing through suitable cooling devices, or it may be admitted from, and exhausted to, the atmosphere.

The object of my invention is to provide 30 simple and effective means for selectively circulating air in a closed circuit or a free or open circuit, as above set forth.

In the accompanying drawings:

Figure 1 is a view, partly in elevation and 35 partly in section, illustrating an embodiment of my invention.

Fig. 2 is a section on line II—II of Fig. 1.

Fig. 3 is a view, partly in elevation and 40 partly in section, showing a modified form of my invention.

Fig. 4 is a section on line IV—IV of Fig. 3.

Referring to Figures 1 and 2, a dynamo-electric machine 1 is provided with a centrally located air outlet port 2 and a plurality of air inlet ports 3 and 4, arranged at each end of the casing. The outlet port 2 communicates with a downwardly extending air outlet passage 5 provided with an opening 6 in one of the walls thereof. A plurality of superposed cooling devices 7 of any preferred type are removably disposed adjacent to the opening 6 and through which the cooling medium passes from the passage 5.

The cooling devices 7 may be conveniently 55 formed of a number of tubes through which water or other cooling liquid may be circulated.

A chamber 8, which will be hereinafter termed the vestibule, is located adjacent to 60 the cooling devices 7 and communicates with a longitudinal passage 9 leading to the external atmosphere. At the sides of the vestibule 8 are transverse passages 10 and 11, 65 preferably of diamond shape in cross-section, which establish communication between the vestibule 8 and the atmosphere and which may be covered by a network or grating, if desired.

It will be understood that the passages 70 may communicate with the atmosphere outside of the building by means of a suitable air duct or trunk, if desired.

The air inlet ports 3 and 4, communicate with downwardly extending passages 12 75 and 13, respectively, which communicate with the vestibule 8 through ports or openings 14 and 15 arranged at the top and bottom thereof. The lateral passages 10 and 11 are provided with oppositely disposed interior diamond-shaped ports 16 which communicate with the vestibule 8 and which may also be covered with a grating or netting, if desired.

Doors or baffles 17 and 18 are horizontally 85 pivoted within the vestibule 8, the axes of the pivots being located at the upper and lower apices of the diamond-shaped ports 16. The doors 17 and 18 are so arranged that they may be moved to a position in 90 which the vestibule 8 is in communication with the air inlet passages 12 and 13 through the top and bottom ports 14 and 15 respectively, and closed with respect to the lateral passages 10 and 11. This position is indicated in full lines in Fig. 1 of the drawing.

The doors 17 and 18, may be moved into the position shown in dotted lines in the drawings, in which position communication 100 is established between the passage 9 and the passages 12 and 13, but closed with respect to the lateral passages 10 and 11.

It will be apparent that, in the first mentioned position of the doors, a closed air circuit may be caused through the machine as indicated by the arrows, whereas, in the second position, the air passes from the longi-

tudinal passage 9 into the inlet passages 12 and 13 to the inlet ports 3 and 4 and, after its exit from the machine, passes from the vestibule 8 through the diamond-shaped openings 10 and 11, to the atmosphere.

Referring now to Figs. 3 and 4, the air inlet and outlet ports, and passages are arranged substantially in the same manner as in the apparatus illustrated in Figs. 1 and 2 of the drawings, with the exception that the lateral passages 10 and 11, are rectangular in cross-section. The top and bottom of the vestibule 8 are provided with diamond-shaped ports 19 and 20 so arranged that one diagonal of the diamond coincides with the longitudinal center line of the apparatus while the other diagonal coincides with the line connecting the junction of the longitudinal passage 9 with the lateral passages 10 and 11. In this arrangement, the vestibule 8 communicates directly with the lateral passages 10 and 11 through openings 21 and 22.

Doors 23 and 24 are vertically pivotally mounted at the junctions of the passage 9 with the passages 10 and 11. In the position of the doors 23 and 24, indicated in full lines in Fig. 3 of the drawings, the vestibule 8 communicates with the inlet passages 12 and 13 through the diamond-shaped openings 19 and 20, respectively, and closed to the longitudinal passage 9. In the position of the doors 23 and 24, indicated by the dotted lines in the drawings, the vestibule 8 is cut off from the openings 19 and 20 and the inlet channels 12 and 13 are in communication with the said openings and also with the longitudinal passage 9.

Communication between the vestibule 8 and the lateral passages 10 and 11 is controlled by doors 25 and 26 which are operatively connected to the doors 23 and 24 for simultaneous movement. The doors are so arranged that when the ports 21 and 22 between the vestibule 8 and the lateral passages 10 and 11 are closed, communication is thereby established between the vestibule 8 and the air inlet passages 12 and 13, the doors 23 and 24 closing the passage 9. This position being shown in full lines in the drawings.

In the position shown in dotted lines, the doors 23 and 24 and the doors 25 and 26 will cause communication to be established between the vestibule 8 and the lateral passages 10 and 11.

In the arrangement shown in the drawing, comparatively narrow vertical partitions or beams 27 and 28, which are respectively provided in front of the cooling devices 7 and in the longitudinal passage 9 are adapted to be engaged by the doors 23 and 24 to arrest or limit the movement thereof.

The air circuit, when the vestibule is open

to the air channels, is shown by the arrows in Fig. 3. The air will pass from the machine through the outlet 2, passage 5 and air cooling devices 7 into the vestibule 8. The current then divides into two separate currents, one of which passes vertically through the opening 19 and passage 12 and into the machine through the port 3. The other current passes downwardly through the opening 20 into the passage 13 and thence upwardly therethrough into the port 4 of the machine.

When the doors occupy the position shown in dotted lines in the drawings, the air passes from the atmosphere through the longitudinal passage 9 and thence through the diamond-shaped openings 19 and 20 into the passages 12 and 13. The air issuing from the machine, passes from the air outlet passage 5 into the vestibule 8 and thence through the ports 21 and 22 into the lateral passages 10 and 11 and thence to the atmosphere.

In the foregoing description, air is described as entering the machine to be ventilated through inlets 3 and 4 and issuing through an outlet 2. It is obvious, however, that the same arrangements may be employed with a circulation of air in the opposite direction by which arrangement the outlet passage becomes the inlet passage and the inlet passages are employed as outlets.

I claim as my invention:

1. A cooling system for an electrical apparatus comprising a casing, a plurality of passages communicating therewith through which air is adapted to be circulated, a cooling device disposed in the path of the air circulated through said passages and means for selectively including said cooling device in a closed circulation of air through said casing and for preventing the air passing through said cooling device from circulating through said casing.

2. A cooling system for an electrical apparatus comprising a casing, a plurality of passages communicating therewith through which air is adapted to be circulated, a cooling device disposed in the path of the air circulated through said passages and means for selectively including said cooling device in the path of the air entering and issuing from said casing to effect a closed circulation of air and for preventing the air entering said casing from passing through said cooling device.

3. A cooling system for an electrical apparatus comprising a casing, a plurality of passages communicating therewith through which air is adapted to be circulated, a cooling device disposed in the path of the air circulating through said passages and means for selectively causing a closed circulation of air through said cooling device and said casing, and an open circulation of air there-

through in which the air contacting with said cooling device is prevented from again entering said casing by discharging the same to the outside atmosphere.

5. 4. A cooling system for an electrical apparatus comprising a casing, having an inlet opening adjacent to each end thereof and an intermediate air outlet opening, an air chamber, a plurality of air passages establishing communication between said chamber and each of said openings, a passage communicating said chamber and the outside atmosphere, a cooling device disposed in said chamber, and means for selectively effecting a closed circulation of air through said casing and said cooling device and an open circulation of air in which the air contacting with said cooling device is prevented from returning to said casing and exhausted to the outside atmosphere.

5. A cooling system for an electrical apparatus comprising a casing, a plurality of passages communicating therewith through which air is adapted to be circulated, a cooling device disposed in the path of the air circulated through said passages and a plurality of co-acting baffle plates for selectively including said cooling device in a closed circulation of air through said casing and for preventing the air passing through said cooling device from circulating through said casing.

6. A cooling system for an electrical apparatus comprising a casing, a plurality of passages communicating therewith through which air is adapted to be circulated, a cooling device disposed in the path of the air circulated through said passages and a plurality of co-acting baffle plates for selectively including said cooling device in the path

of the air entering and issuing from said casing to effect a closed circulation of air and for preventing the air entering said casing from passing through said cooling device.

7. A cooling system for an electrical apparatus comprising a casing, a plurality of passageways communicating therewith through which air is adapted to be circulated, a cooling device disposed in the path of the air circulating through said passageways and a plurality of co-acting baffle plates for selectively causing a closed circulation of air through said cooling device and said casing, and an open circulation of air therethrough in which the air contacting with said cooling device is prevented from again entering said casing by discharging the same to the outside atmosphere.

8. A cooling system for an electrical apparatus comprising a casing having an inlet opening adjacent to each end thereof and an intermediate air outlet opening, an air chamber, a plurality of air passages establishing communication between said chamber and each of said openings, a passage communicating said chamber and the outside atmosphere, a cooling device disposed in said chamber, and a plurality of co-acting baffle plates for selectively effecting a closed circulation of air through said casing and said cooling device and an open circulation of air in which the air contacting with said cooling device is prevented from returning to said casing and exhausted to the outside atmosphere.

In testimony whereof, I have hereunto subscribed my name this tenth day of September, 1920.

JOHN ERNEST JOLLEY.
